UNITED STATES PATENT OFFICE.

EDWIN J. MCCORMICK, OF SYRACUSE, NEW YORK, ASSIGNOR TO THE
McCORMICK MANUFACTURING COMPANY, OF NEW YORK, N. Y.

DESIGN FOR A NUT FOR EXPANSION-FASTENERS.

SPECIFICATION forming part of Design No. 32,446, dated April 3, 1900.

Application filed March 31, 1898. Serial No. 675,995. Term of patent 14 years.

To all whom it may concern:

Be it known that I, EDWIN J. MCCORMICK, of Syracuse, in the county of Onondaga, in the State of New York, have invented and 5 produced a new and original Design for Nuts for Expansion-Fasteners, of which the following is a specification, reference being had to the accompanying drawings, forming a part thereof.

10 Figures 1 and 2 are different face views of a nut for expansion-fasteners, showing my new design. Fig. 3 is a rear end view of the nut. Fig. 4 is a front end view of the said nut.

As shown in the drawings, the leading or 15 material feature of my design consists of a tapered nut, which when viewed in face view presents the appearance of a frustum of a cone, having its periphery provided with longitudinal ribs and grooves, the sides of the 20 grooves being inclined toward each other from the larger end of the nut.

A is a tapered nut of my design. The periphery of the nut A is provided with oppositely - arranged substantially-wedge-shaped 25 fins a, which extend lengthwise of said nut, as seen in Figs. 1 and 2, and increase in width

toward its larger end. The portions of the periphery of the nut interposed between the fins a are formed with longitudinal substantially-V-shaped ribs a' and grooves a''. The 30 sides of said grooves incline toward each other from the larger end of the nut, as best seen in Figs. 1 and 2. The contour of a nut showing my design and the arrangement and shape of its fins and interposed grooves im- 35 part a characteristic appearance to said nut.

Having described my invention, what I claim as new, and desire to secure by Letters Patent, is—

The design for a nut for expansion-fasteners, substantially as herein shown and described. 40

In testimony whereof I have hereunto signed my name, in the presence of two attesting witnesses, at Syracuse, in the county of 45 Onondaga, in the State of New York, this 8th day of January, 1898.

EDWIN J. MCCORMICK.
